UNITED STATES PATENT OFFICE.

CURTISS F. SMITH, OF DETROIT, MICHIGAN.

SNAP DRUM SWITCH.

1,417,284.

Specification of Letters Patent. Patented May 23, 1922.

Application filed February 21, 1921. Serial No. 446,811.

To all whom it may concern:

Be it known that I, CURTISS F. SMITH, a citizen of the United States of America, residing at Detroit, in the county of Wayne 5 and State of Michigan, have invented certain new and useful Improvements in Snap Drum Switches, of which the following is a specification, reference being had therein to the accompanying drawings.

10 The invention relates to rotary electric switches and more particularly to the drum type, such, for instance, as are used in controllers for electric motor vehicles. It is the object of the invention to obtain a construction which will give an exceedingly quick opening of contacts and which is positive in its action and simple in its construction. To this end the invention consists in the construction as hereinafter set forth.

15 In the drawings:

Figure 1 is a plan view of the switch;

Figure 2 is a cross-section therethrough; and

20 Figures 3 and 4 are perspective views of the star wheels detached.

25 A is the drum or body of the rotary switch on which the contacts B are mounted to successively engage the stationary brush contacts C. D and E are star wheels arranged in axial alignment with the drum, the former being fixedly mounted to the end of the drum, and the latter having a limited independent rotation. These star wheels are adapted to cooperate with rollers 30 F mounted upon levers or dogs G and G', which are under tension of springs H holding said rollers in engagement with the notches of the respective star wheels. The star wheels D and E are spaced from each 35 other and between the same is arranged a lug I projecting from the one and a lug J projecting from the other, said lugs being in radial alignment. K and K' are springs, preferably leaf springs, which are bolted or 40 otherwise secured to the lug I, as indicated at L, and which embrace the lug J. These springs extend beyond the axis of the drum and star wheels and the arrangement is such that when said star wheels are moved rotationally in relation to each other, one or the 45 other of said springs will be flexed. This flexing will place a resilient torque upon the star wheel, which is not directly actuated, with the result that it will force the roller F 50 out of engagement with the notch in the

wheel and permit engagement in the succeeding notch.

It is desirable to make this action absolutely certain, giving the drum an initial positive start from rest, if necessary, after 55 which the springs act instantaneously, and also to prevent too great a relative motion between the two star wheels. This is accomplished by a lost-motion coupling between the two star wheels, comprising a V-shaped 60 lug M forming an extension from one star wheel, and a V-shaped notch N of greater angle on the other star wheel in which the lug M engages. The clearance for the lug M in the notch N is such as to allow the 65 directly-actuated star wheel to move its roller F partly or completely out of engagement with its present notch before moving the other, thereby placing the springs under strain which imparts a snap-action to the 70 drum, either when the spring strain alone becomes sufficient to overcome the retaining action of the drum star wheel roller and contacts friction or when given an initial 75 impulse by the lug M and notch N coming 80 in contact. Further movement than desired is prevented by the retaining action of the star-wheel rollers and the opposing action of the leaf springs. Also, when the 85 cooperating star wheel is actuated, the first-mentioned star wheel will usually complete its movement and will be re-engaged by the roller F before the second star wheel is fully disengaged from its roller F. Thus when 90 the snap occurs, it will move the second star 95 wheel to a position for engagement with the roller F and further movement will be prevented by the opposing spring. Therefore, while the movement which breaks electrical contact is very quick, this movement is arrested at an exactly predetermined point.

To hold the star wheels and drum in axial alignment and to provide means for actuating the star wheel E, these parts are mounted upon a shaft O, which is revoluble in bearings in the drum but is rotatively fixed to the star wheel E. This shaft may be provided with any suitable actuating handle (not shown) by means of which it can be turned in either direction to cause the shifting of 105 the switch from one position to another.

What I claim as my invention is:

1. In an electric switch, the combination with a rotatable member having a plurality of electrical contacts mounted thereon, of a 110

pair of star wheels, one having a positive driving engagement with said member and the other having a limited relative movement thereto, yieldable dogs for engagement 5 with the respective star wheels, a lost-motion positive drive connection from one star wheel to the other, permitting a movement of the actuating member before positively communicating said movement to the actuated member, and a resilient torque connection 10 between said star wheels placed under tension by the initial movement of the actuating member.

2. In an electric switch, the combination 15 with a rotatable member having a series of contacts mounted thereon, of a pair of star wheels, one being rotatively fixed thereto, resilient latch dogs for engaging said star wheels, a lost-motion drive connection from 20 one star wheel to the other, permitting of independent rotation through a predetermined angular distance, and a resilient torque connection between said star wheels placed under tension by the relative rotation 25 thereof.

3. In an electric switch, the combination 30 with a rotatable member and a series of contacts mounted thereon, of a pair of star wheels, the one having a positive connection therewith, means for rotatively actuating the other star wheel, lugs projecting from 35 said star wheels in radial alignment, a spring secured to one of said lugs and engaging the other lug for yieldably holding the same in radial alignment, a projection from one of said lugs engaging a recess in

the other star wheel forming a lost-motion driving connection between said star wheels, and resilient latch dogs for engaging said star wheels.

4. In an electric switch, the combination 40 with a rotatable member having a series of contacts mounted thereon, of a pair of star wheels, one being positively connected thereto, resilient latch dogs for engaging said star 45 wheels, lugs projecting from said star wheels on opposite sides of the common axis thereof in radial alignment with each other, springs secured to one of said lugs and embracing the opposite lug, and a projection from one 50 of said lugs extending into a recess in the other star wheel with clearance to form a lost-motion driving connection.

5. In an electric switch, the combination 55 with a rotatable member, of a series of electric contacts mounted thereon, a pair of star wheels, one being positively connected thereto, resilient latch dogs for engaging said star wheel, a lug on one of said star wheels extending radially and crossing the axis thereof, a lug on the other star wheel extending in radial alignment with said first-mentioned lug on the opposite side of the axis, a pair of leaf springs secured to the last-mentioned lug and embracing the first-mentioned lug, and a V-shaped lug projecting from one of said lugs and engaging a V-shaped aperture in the other star wheel, the angle being such as to provide a lost-motion 60 connection, for the purpose described. 65

In testimony whereof I affix my signature.

CURTISS F. SMITH.
